UNITED STATES PATENT OFFICE.

ALFRED M. LANE, OF ST. LOUIS, MISSOURI, ASSIGNOR TO MONARCH METAL WEATHER STRIP COMPANY, OF ST. LOUIS, MISSOURI, A CORPORATION OF MISSOURI.

WEATHER-STRIP FOR METAL-WINDOW CONSTRUCTIONS.

1,049,373.

Specification of Letters Patent.

Patented Jan. 7, 1913.

Application filed August 25, 1911. Serial No. 646,022.

To all whom it may concern:

Be it known that I, ALFRED M. LANE, a citizen of the United States, and a resident of the city of St. Louis and State of Missouri, have invented a new and useful Improvement in Weather-Strips for Metal-Window Constructions, of which the following is a specification.

This invention relates to weather strips and more particularly to weather strips or guards to be applied to metal window constructions.

Difficulty has been experienced in applying weather strips to metal window constructions. Attempts have been made, with little or no success, to produce a weather strip which can be applied generally to the ordinary metal window frames and sashes, the principal faults being in the manner of attachment and the lack of flexibility in the strip.

My invention, therefore, has for its principal objects to produce a device which is inexpensive and easily applied to window sashes and frames constructed of metal, to produce a strip which possesses sufficient flexibility to permit of its application to windows wherein there is considerable play between the sashes and guideways, and to attain certain other advantages hereinafter more fully appearing.

The invention consists in the parts and in the arrangements and combinations of parts hereinafter described and claimed.

In the accompanying drawings which form part of this specification and wherein like symbols refer to like parts wherever they occur, Figure 1 is a horizontal section through one side of the window casing and adjacent portions of the upper and lower sashes; Fig. 2 is a fragmentary perspective view of the rib strip member; Fig. 3 is a similar view of the groove strip member; Fig. 4 is a fragmentary view, partly in horizontal section and partly in top plan and on an enlarged scale, showing the two coöperating weather strip members applied; and Fig. 5 is a fragmentary section through a portion of the window casing adjacent to one of the burred perforations which receive the securing screws for the weather strip members.

The precise construction of the window frame or casing and sashes forms no part of my invention. Hence no detail description

will be given except as to so much of the structure as will give a clear understanding of the invention.

In the drawings, a window casing 1 is illustrated as being constructed of sheet metal and having guideways 2 and 3 formed therein for the lower and upper sashes 4 and 5, respectively. The parting strip or bead 6 and outer guide strips or beads 7, as shown, are formed integral with the window casing. In fact, the shell of the side members of the window casing are constructed of single sheets. It is to be here noted, that in practically all metal window frame constructions, access cannot be gained to the interior of the shell which makes it all the more difficult to apply weather strips, as securing screws or bolts cannot be secured on the inside of the shell unless special provision is made in course of construction.

As shown in the drawings, the weather strip comprises two metal strips 8 and 9, respectively. The strip 8 has one of its marginal portions rolled or beaded, as at 10, to provide an undercut groove, and the strip 9 has one of its marginal portions rolled or beaded to provide an undercut rib 11 which slidably fits in said groove 10. The strip 8 is secured near its opposite margin by a series of screws 12 to the face of the window sash, while the strip 9 is secured by a series of screws 13 to the face of the sash-retaining rib or bead 7 on the window frame.

In applying the fastening screws, the strips 8 and 9 are perforated to receive them and the sash and window frame are punctured with a taper punch. In punching the perforations in the sash and window frame burs 14 are turned up on the inside thereof on a taper. After the holes have been punched they are tapped to provide screw threads which fit the threads of the securing screws 12 and 13. As the screws are being applied and tightened, the burs 14 are drawn toward and impinged tight against the screws, forming an effective lock which prevents the screws from working loose. By dipping the screws in salt water or some other corrosive, the screws are further held by the rust and corrosion which eventually forms.

To prevent the strips 8 and 9 from buckling between the points where the screws are inserted, they are curled or flanged, as at 15, at their margins. By this arrangement,

2
the base portions of the strips 8 and 9 do not bear flatwise against the sash or frame, as the case may be, but bear at the edges of the portions 15 and bends 16 which are formed 5 in said strips.

The portion of the strip 8 at the base of the bead 10 is offset outwardly so as to make room for the coöperating marginal portion of the strip 9 and give some clearance between the latter and the face of the sash. 10 The portion of the strip 9 between the bend 16 and a bend 17 located adjacent to the rib 11 is turned away from the face of the retaining rib or bead 7 on the window frame 15 at a considerable angle.

Preferably, the strip 9 is made of a relatively resilient or pliable metal, while the strip 8 is relatively rigid so that its groove bead 10 will not be sprung out of shape 20 when the strain is put upon it by the shifting of the window sash horizontally in its guideways. The strip 9 being resilient or flexible will yield to allow the sash the freedom of its play in the guideways, and the 25 rib bead 11 of the strip 9 being smaller than the groove bead 10 of the strip 8 and its sides being brought close together at its base, it is sufficiently rigid to resist pulling strains. It is also held by the mouth portion 30 of the groove bead which fits it snugly at the base. The angularly extended portions between the bends 16 and 17 of the two strips on opposite sides of the window frame permit the sash to have considerable end- 35 wise movement horizontally, toward either side as well as transversely.

Obviously, while the strip is set forth as being specially applicable to metal window constructions, it can be readily applied to 40 wooden constructions. So, too, it is obvious that the weather strip may be applied to the parting strip or bead 6 instead of the retaining strip or bead 7 as shown; and the device admits of considerable modification 45 without departing from my invention. Therefore, I do not wish to be limited to the specific construction and arrangement shown.

What I claim is:

50 1. A weather strip comprising two metal strips, one adapted to be fastened to the window frame and the other to the window sash, one of said strips being relatively rigid and having an offset marginal portion provided with an undercut groove extending longitudinally thereof, and the other strip 55 being relatively flexible and having an

undercut rib thereon extending longitudinally near one of its margins, said flexible strip underlying the offset portion of said rigid strip and the rib being slidably fitted in the groove of said other strip, the opposite marginal portion of said flexible strip extending at substantially right angles to said rigid strip, said flexible strip being bent 60 between its marginal portions so as to normally be free from contact with the member to which said strip is secured.

2. A weather strip comprising a relatively flexible metal strip adapted to be fastened throughout its length near one of its margins, the intermediate portion of said strip being bent at an angle less than a right angle and the opposite marginal portion being bent at substantially right angles to 70 said first mentioned marginal portion, the free marginal portion of the strip being rebent throughout its length to provide a rib, and a relatively rigid metal strip adapted to be secured throughout its length 75 near one of its margins and the opposite marginal portion being adapted to overlap the marginal portion of said flexible strip on which the rib is formed, said overlapping marginal portion of the rigid strip being 80 rebent to form a groove adapted to slidably fit over said rib.

3. The combination with the opposite sides of a window casing and a sash slidably fitted in said casing, of relatively rigid 90 metal strips secured throughout their length near one margin to the exposed face of the sash adjacent to the sides of the window casing, the opposite marginal portions of 95 said strips being free, and relatively flexible metal strips having one of their marginal portions arranged to overlap the free marginal portions of the respective rigid strips and slidably engage the same longitudinally but being interlocked therewith against lateral separation, the opposite marginal portions of said flexible strips being turned at substantially right angles to the first mentioned marginal portions and secured throughout their length to said window casing, the intermediate portions of said flexible strips being bent away from the respective sides of the casing adjacent thereto. 100

Signed at St. Louis, Mo., this 18th day of August, 1911.

ALFRED M. LANE.
